UNITED STATES PATENT OFFICE.

STEPHEN C. PRICE, OF LOUISIANA, MISSOURI, AND EARL E. RICHARDSON, OF QUINCY, ILLINOIS, ASSIGNEES, BY DIRECT AND MESNE ASSIGNMENTS, TO P. R. B. PUMP CO., OF HANNIBAL, MISSOURI, A CORPORATION OF MISSOURI.

OIL DISPENSING AND MEASURING DEVICE.

1,380,590.

Specification of Letters Patent. Patented June 7, 1921.

Application filed July 28, 1919. Serial No. 313,899.

To all whom it may concern:

Be it known that we, STEPHEN C. PRICE and EARL E. RICHARDSON, citizens of the United States, and residents of Louisiana, 5 Missouri, and Quincy, Illinois, have invented certain new and useful Improvements in Oil Dispensing and Measuring Devices, of which the following is a specification containing a full, clear, and exact description, 10 reference being had to the accompanying drawings, forming a part thereof.

This invention relates to a dispensing device, and has for its primary object a measuring device, which can be attached to the 15 original package and the contents of the package be expelled by air pressure.

A further object is to provide the original package of an oil containing device with a safety valve, a pressure gage and a measuring 20 device so that predetermined amounts of the contents may be dispensed.

In the drawings:

Figure 1 is a view of our device with all parts attached and portions in section.

Fig. 2 is an enlarged view of the pressure gage, safety valve and air valve.

Fig. 3 is an enlarged view of the method employed in connecting the dispensing mechanism to the tank.

Fig. 4 is a sectional view of the attachment made use of when it is desired to drain the tank without measuring the contents.

The construction of our device is as follows:

We employ a tank 5, which is of ordinary construction, and which may contain gasoline, lubricating oil, or in fact any other liquid. This tank or container is provided with openings 6 and 7, and in the opening 40 6 is secured a nut 8, this nut being provided with internal and external threads, the internal thread portion receiving a nipple 9 and to this nipple is attached a cross 10, secured to the cross are the safety valve 11, the pressure gage 12 and the air valve 13,

in the opening 7 is secured the screw threaded plug 14 which is likewise provided with a threaded opening, see Fig. 3, and through this opening is threaded the pipe 15, this 45 pipe extending practically to the bottom 17 of the container or drum 5.

The projecting end 18 of the pipe 15 is provided with a swivel coupling 19, which is secured to a pipe or goose neck 20, this

pipe being provided with the ordinary 55 valve 21 and a swivel coupling 22. Secured to the swivel coupling 22 is a nipple 23 which in turn is secured to a valve 24, which is secured to a measuring chamber 25.

This measuring chamber has a transparent 60 cylindrical portion 26 and a measuring gage 27, the object of which is to indicate the amount of fluid withdrawn from the measuring chamber. The bottom of this measuring chamber is tapered, as indicated 65 by the numeral 28 so as to allow a free discharge of its entire contents, and a valve 29 is secured to the bottom of this chamber so that the contents can be withdrawn therefrom.

The gage 27 is graduated so that any predetermined amount of liquid may be withdrawn. The valve casing 13 is provided with a spring actuated valve 30 which is of the mushroom type, the object of this being to allow air to be pumped into the container 5 but not allow it to escape from the container.

This air will lodge on the top of the liquid in the container and force the contents 80 out through the pipe 15, the safety valve 11 acting to prevent excess pressure from forming in the container due to expansion of the liquid contained therein, and the gage recording the amount of pressure in 85 the tank above the liquid, as it is a well known fact that liquid cannot be compressed, thus only the air above the liquid will be compressed in the event of any expansion taking place.

We may, if desired, remove the measuring portion of our device and substitute the nozzle 31 as shown in Fig. 4, to which a hose or pipe may be attached when it is desired to drain the tank of its contents, or when the 95 tank is used for spraying purposes, such as for orchards, flowers or other agricultural purposes.

In the upper end of the measuring compartment 25 we place an air vent 32. This 100 vent is opened while filling the measuring compartment or drawing off its contents, so that no vacuum or compression will be formed during either operation. This vent is mechanically controlled by the float 105 valve 33.

The operation of our device is as follows: It being a well known fact that the drums

or containers or packages of oil, etc., especially when constructed of metal are provided in at least one of their heads with screw threaded openings, it is our intention 5 to secure the device within the openings, and attach the valve 13 either to an air pump or some other suitable source of air pressure. This will cause the contents of the drum to be driven upward through the 10 pipe 15 into the measuring device or through the spray nozzle when it is employed.

When our device is used for dispensing lubricating oil, fuel oil, or in fact any other 15 liquid which is dispensed by the quart, gallon, etc., the measuring device is attached and an accurate amount can be withdrawn without the use of measuring pumps, but when it is desired to use this device for 20 spraying or draining the entire tank, the measuring device is detached and the nozzle shown in Fig. 4 is substituted, and then a suitable hose connection attached to the nozzle. The valve 21 only serves the purpose of 25 closing the pipe or goose neck 20 so that the contents of the container 5 will not be lost when the measuring device is removed therefrom, as the valve 24 will be removed at the same time.

30 It will be readily seen from the drawings that if the valve 21 is not closed, and the measuring device removed, the contents of the container 5 would be lost as the air pressure would drive them upward and out 35 through the pipe 15, there being no relief valve to release this air pressure, nor is any desired by us, as one of our ideas is to maintain pressure within the container 5 at all times, until its entire contents are without 40 drawn.

Our invention has been developed with the idea of using the ordinary container in which gasoline is delivered as a tank from which the gasoline may be measured and 45 dispensed. These containers are air-tight so that they will hold the compressed air which may be forced into them thus making it unnecessary to provide in an oil dispensing and measuring apparatus supplemental tanks or 50 reservoirs for containing air under pressure. These containers are usually of such size that they may be easily moved from place to place. It is therefore desirable to provide means for adjusting the measuring 55 device 25 with reference to the tank to suit the convenience of those who will use it, and this capability of adjustment is provided by the swivel coupling 19 uniting the goose neck with the delivery pipe 15. By means 60 of this the measuring device may be swung to one side or the other of the tank and close to the tank or more distant therefrom as circumstances may suggest. This adjustment of the measuring device would under certain

conditions carry the scale 27 with which it 65 is provided into such position that it could not be readily observed, and we therefore provide a swivel connection 22 between the measuring device and the free end of the goose neck. As has been already described, 70 this connection not only permits the adjustment of the measuring device just described, but also its removal and the substitution therefor of a connection like that shown in Fig. 4. 75

Having fully described our invention, what we claim is:

1. An oil dispensing and measuring device, comprising a single tank for storing the oil and air under pressure, and provided 80 with screw-threaded openings, an internally and externally screw-threaded nut secured in each opening and providing air-tight connections for said openings except through the nuts, a cross shaped fitting detachably 85 mounted in one of said nuts, a pressure gage and safety valve carried by said fitting, an outwardly seating check valve for admitting and retaining air under pressure carried by 90 said fitting, a discharge pipe located in said tank having its upper end screw seated in the other nut, a goose neck provided with a cut-off valve, a swivel connection between the 95 goose neck and discharge pipe permitting the same to be swung and adjusted to different sides of the tank, a measuring chamber, a swivel connection between the measuring chamber and goose neck, whereby the latter may be disconnected from the goose neck and adjusted so as to bring the scale on 100 the measuring chamber in desired position independent of the adjustment of the goose neck.

2. An oil dispensing and measuring device, comprising a tight tank, a connection 105 whereby air under pressure may be delivered to and retained in the tank, a discharge pipe connected with the tank, leading from the inside thereof near its bottom to the outside, a goose neck, a measuring chamber provided 110 with a reading scale carried by the goose neck, a swivel connection between the discharge pipe and the goose neck permitting the measuring chamber to be swung around the tank to a desired position, and a swivel 115 connection between the measuring chamber and the goose neck whereby the former may be adjusted to bring the scale to the desired position independent of the adjustment of the goose neck.

In testimony whereof, we have signed our names to this specification, in the presence of two subscribing witnesses.
